CASKET

Francis R. Christian, River Forest, Ill., assignor to The Merit Company, Chicago, Ill., a corporation of Illinois

Filed Apr. 20, 1964, Ser. No. 79,586

Term of patent 14 years

(Cl. D19—1)

The essential features of my design reside in the portions shown in full lines in the drawings.

I claim:

The ornamental design for casket, as shown and described.
